ADJUSTABLE DIE

Frederick L. Patterson, Masury, Ohio

Application June 22, 1953, Serial No. 363,324

4 Claims. (Cl. 164—15)

This invention relates to an adjustable shearing die and particularly to an adjustable die particularly constructed to provide successive transformer laminations from a strip of lamination steel.

This application is a continuation-in-part of my application Serial No. 752,195, filed June 3, 1947, now Patent No. 2,647,575, issued August 4, 1953.

In the construction of electro-magnetic devices such as transformers it has long been known that the reluctance of the magnetic path is decreased if the magnetic flux flows in the direction of the grain of the laminated pieces forming the magnetic structure. Also, it has long been known that when steel is elongated by rolling that the grain of the steel is in the direction of the rolling. Consequently, it is practiced in this art to cut laminations for magnetic structures so that the path of the flux will follow the grain of the laminations and such construction is provided even though it is necessary to waste a material portion of the steel to secure such orientation of the grain in the flux path.

In the construction of transformer laminations it is desirable when possible to cut the laminations from a strip of lamination steel of the exact width of the lamination to be finished and to trim the ends of the laminations to fit into the structure. It has heretofore been customary to cut the strip into the successive lengths to provide the lamination pieces and to trim the pieces with shearing dies to provide the necessary end structures. Since most of the laminations have the diagonal end face such construction is not only wasteful of material but is also wasteful of labor in that the devices must be handled several times and frequently sheared several times in order to get the proper contour.

In applicant's above noted application, a shearing die was constructed which forms the successive ends of the blanks so that the rear end of one lamination and the front end of another lamination are simultaneously formed by the shear operation so that the diagonal portions of the end pieces of the laminations may be overlapped or arranged in side by side relation so that the minimum material will be utilized to produce the maximum number of laminations. The present application provides a die structure which not only forms the adjacent ends of two laminations at a single cut but eliminates most of the wastage of material between the two ends so that the minimum amount of material will be utilized and a single cut provide both the front of one lamination and the rear of the next.

The die structure according to the present invention is constructed of male and female parts so arranged that the shear will be provided without much waste of material between the adjacent ends of successive laminations.

It is accordingly an object of the invention to provide an improved shear die.

It is a further object of the invention to provide a shear die for simultaneously forming the ends of adjacent sections without wasting material between the sections.

It is a further object of the invention to provide a

2

shear die specifically constructed to build transformer laminations.

Other objects and many of the attendant advantages of the present invention will be apparent from the following 5 detailed description taken in conjunction with the accompanying drawing in which:

Figure 1 is a plan view of the guide and stop arrangement of a shearing die to feed on an elongated strip of transformer steel to be conformed into transformer 10 laminations;

Figure 2 is a side elevation of the shear die according to the invention and shows the shear die in open position;

Figure 3 is a cross section through the die taken substantially on the plane indicated by the line 3—3 of Figure 2 and showing a bottom plan view of the male die;

Figure 4 is a cross section through the die structure taken substantially on the plane indicated by the line 20 4—4 of Figure 2 and showing a top plan view of the female die;

Figure 5 is an enlarged cross section of the die structure with the male structure indicated by hatched lines and showing one adjustment of the die;

Figure 6 is a view similar to Figure 5 and showing another adjustment of the die;

Figure 7 is a vertical sectional elevation through the die in open position taken substantially on the longitudinal center line of the die; and

Figure 8 is a plan view of a lamination cut from the strip by the improved die.

In the exemplary embodiment according to the invention a shear stand is provided having a forward guide 10 and a rear guide and stop member 12 with lateral guide members 14 and 16 on the forward guide block 10 for slidably engaging the edge of a strip 18 of rolled steel suitable for forming transformer laminations. Likewise, side guides 20 and 22 are provided on the forward guide block 12 and a suitable stop guide 24 is slidably 25 adjustable between the side guides 20 and 22 as by means of the guide slots 26. Space between the blocks 10 and 12 will be occupied by a shear die presently to be described. The finished lamination pieces may be removed from the stop block 12 by any desired means.

The shearing die comprises a bottom base member 30 and a top base member 32 arranged in aligned formation with each other by means of slide rods 34 and 36 which maintain the bases 30 and 32 in proper alignment with each other. A main female die 38 is mounted on the bottom base member 30 and a main male die member 40 is mounted on the upper base 32. The main male and female die members are arranged in longitudinal relation with respect to the center line 42 of the path of travel of the strip 18 and are arranged with the apices 44 of the female die and 46 of the male die in substantial opposition to each other but in spaced longitudinal relation and offset laterally on opposite sides of the center line 42. The longitudinal offset relation of the V-shaped die members 38 and 40 provides a relation by which the V-face 48 of the V-shaped die member 38 is opposed to the V-face 50 of the V-shaped die member 40. The V-faces 48 and 50 being in parallel offset relation to each other. Likewise the V-face 52 of the V-shaped die member 38 and the V-face 54 of the V-shaped die member 40 are in parallel offset relation to each other.

A first pair of shear blades 56 and 58 are applied to the opposing faces 48 and 50 of the V-shaped members 38 and 40. The shear blades 56 and 58 are identical in construction and are provided with a plurality of apertures 60 in which are secured suitable fastening means such as the bolts 62. The end 64 of the shear blade

3

56 is of a different length than the end 66 and the apertures 60 in the fasteners 62 are so arranged that the blade 56 may be mounted in either direction on the V-shaped die member 38 so that it will be extended a greater or lesser degree past the apex 44 thereof. Likewise, the 10 blade 58 has an end 68 identical with the end 64 of the blade 56 and an end 70 identical with the end 66 of the blade 56. Likewise, the aperture 60 and the fastener 62 of the blade 58 are so positioned that the blade 58 may likewise be reversed to produce the different overhang over the apex 46 of the die member 40.

15 Parallel offset mountings of the blades 56 and 58 produce a portion 72 which is in shear relation with each other so that the reciprocation of the die members 38 and 40 will cause a shearing along this edge. Likewise, it will be noted in Figure 6 that when the blades 56 and 58 are reversed the shearing section or portion 74 of a different length will be provided.

20 A pair of lateral male die members 80 and 82 are provided in opposition to the die member 38 and particularly to the V-faces 48 and 52 thereof. Likewise, female die members 84 and 86 are provided in opposition to the V-faces 50 and 54 of the die member 40.

25 A male die member 80 opposed to the V-face 48 is provided with a shear blade 88 and the female die member 86 opposed to the V-face 50 of the male die member 40 is provided with a shear blade 90 which is identical in shape and construction to the shear blade 88. The blade 88 is provided with an end extension 92 and an end extension 94 of different lengths. Likewise, the blade 90 is provided with an end member 96 and an end member 98. The end members 96 and 92 being identical and the end members 94 and 98 likewise being identical. It is particularly noted that the blades 56 and 90 are so mounted that the cutting edges thereof form a continuous straight female cutting edge from end to end of the blades and extending diagonally across the die. Likewise the blades 88 and 58 form a continuous male cutting edge which is in shear relation with the combination blades 56 and 90. Ends 92 and 94 of the blade 88 are bevelled to provide an outside recess 100 in the continuity of the blades 88 and 58 and likewise the blade 90 is provided with the ends 96 and 98 bevelled to provide the recess 102 in the continuity of the blades 56 and 90.

30 It will be apparent from an inspection of the die arrangement that by reversing the die members 56 and 58 and simultaneously the die members 88 and 90 the amount of the shear between the portions 72 and 70 will be altered. Likewise, the offset of the end of the dies will be altered as shown in Figures 5 and 6 when the short ends of the members 56 and 58 are overhanging the apices 44 and 46 an offset indicated at 110 and 112 will be produced and when the long ends of the blades 56 and 58 are overhanging the apices 44 and 46 a much wider offset will be produced as shown at 114 and 116.

35 Shear blades 120 and 122 are mounted on the members 38 and 40, respectively, for the small angle of overlap and the blades 120 and 122 are of sufficient width that they abut with and form a square line or cutting edge 124 which is a continuation of the cutting edge of the end 64 and a cutting edge 126 which is a continuation of a cutting edge of the end 68. When the blades 56, 58, 88 and 90 are reversed, blades 120 and 122 are replaced by similar blades 130 and 132 which likewise provide cutting edges 134 and 136 which are continuations of the cutting edges of the ends of the blades 56 and 58.

40 A shear blade 140 is mounted on the lateral male die 82 and is provided with a tapered end member 142 which extends into the apex 102 between the die members 56 and 90. Likewise, a blade 144 is mounted on the female die member 84 and cooperates with the blade 122 and is provided with a diagonal point 146 which extends into and fills the apex 100 between the blade 58 and the blade 88. When the blades 56, 58, 90 and 88 are

45 interchanged the blades 140 and 144 are changed for blades 150 and 152 which have tapered end portions 154 to extend into the displaced apex 102 and the blade 152 has a tapered end portion 156 to extend into the apex 100 between the shear blades 58 and 88.

50 In order to permit the male die 80 to pass the female die 84 a cutting blade 160 is placed on the male die member 80 and a cooperating cutting blade 162 is placed on the female die member 84. The cutting edge of the blade 160 is made continuous with the bevelled back edge of the blade 88 and preferably the bevel and the cutting edge of the blade 160 are diametrically transverse to the center line 42 of the direction of travel of the blank 18.

55 Likewise the die member 82 is provided with a blade 164 and the female die member 86 is provided with a blade 166 with the cutting edge of the blade 166 being a continuation of the bevel of the blade 90 which is also perpendicular to the axis of travel of the blank.

60 When the cutting blades 56, 58, 88 and 90 are reversed the blades 160 and 162 are replaced by blades 170 and 172 which are of sufficient width so that they again meet the bevel of the blade 88 and fill the recess between the blades 88 and 58. Likewise, the blade 164 is replaced by blade 174 and the blade 166 by blade 176.

65 As is well understood in the art, base member 30 carrying the female die members 38, 84 and 86 is cut out under the end of the path of travel of the male dies to provide recesses 180, 182 and 184 so that pieces cut out by the 70 passage of the male die will fall below the path of travel of the male die.

75 In operating the shearing dies to produce the transformer lamination 190 having the forward point 192 offset from the center line of the blank 18 and the rear point 194 offset from the opposite direction from the center line in the blank 18 the dies are assembled as shown in Figure 5, the blades 56, 58, 88 and 90 set up to produce the small offset from a center line 42 and the blank 18 will be fed through the side guides 16 and 14 and the end will be cut by the operation of the die after which the end of the blank 18 will be projected against the stop 24 after which the dies will again be reciprocated to produce the desired number of parts 190.

80 When it is desired to utilize a number of parts having the larger offset as shown in Figure 6, the blanks will be fed as before to produce a plurality of laminations 196. Obviously, any number of strips or a continuous strip 18 may be fed through the dies to produce the desired number of laminations 190 or 196 so that the desired size of transformer leg may be constructed.

85 For purpose of exemplification, the die has been set up to produce two particular offsets as shown at 110 and 112, and 114 and 116. Obviously, the blades 56, 58, 88, and 90, together with the subsidiary blades could be replaced by blades of different size to produce different offsets besides the ones shown.

90 Also, it will be obvious that the present invention provides a shearing die having reversible parts to produce a dislocation of the offset of a lamination blank so that lamination blanks having a desired point offset can be readily constructed thereon.

95 For the purpose of exemplification, a particular embodiment of the invention has been shown and described according to the best present understanding thereof. However, it will be apparent to those skilled in the art that changes and modifications may be made and arranged in the construction and arrangement of the parts herein without departing from the true spirit and purpose of the invention.

100 What is claimed as new is as follows:

1. For use in a shear press for producing a plurality of transformer core laminations from an elongated strip of transformer steel having a width corresponding to the width of the finished laminations, said laminations having 105 similarly shaped pointed ends spaced inwardly from the

edges of the strip with the apices of said points being disposed on opposite sides of the longitudinal center line of the lamination and the grain structure of the lamination being parallel to the longitudinal center line of the lamination, and side guides for engaging the sides of the steel strips, a waste eliminating shearing die for simultaneously forming by shearing the ends of adjacent laminations from the strip comprising a main V-shaped female die member, a main V-shaped male die member, said main female and male die members being longitudinally arranged with respect to the path of travel of said strip, the apices of said female and male die member being disposed in proximity and disposed on opposite sides of the path of travel of said strip, the V-faces of said main die members being in offset parallel relation, a portion on one face of the female die member being opposed to a portion of one of the faces of said male die member, shear blades mounted on said opposed faces, a portion of said shear blades being in shearing relation to each other, said blades being reversible to vary the extent of the engagement of said blades, second shear blades on the remaining faces of said female and male die members the thickness of said second blades being determined by the position of said first mentioned blades, a pair of lateral male die members opposed to the faces of said main female die member, a pair of lateral female die members opposed to the faces of said main male die member, shear blades mounted on said lateral die members and cooperating in shearing relation with said first and second shear blades.

2. For use in a shear press having side guides and stop guides for producing a plurality of transformer core laminations from an elongated strip of transformer steel having a width corresponding to the width of the lamination and a grain structure parallel to the longitudinal center line of the strip, said laminations having similarly shaped pointed opposite ends, spaced inwardly from the edges of the strip with the apices of said points disposed on opposite sides of the longitudinal center line of the laminations, a waste eliminating shearing die for simultaneously forming the ends of adjacent laminations, comprising a main V-shaped female die member, a main V-shaped male die member, said main die members being longitudinally arranged with respect to the path of travel of the strip, the apices of said main female and male die members being arranged in opposition and disposed on opposite sides of the center-line of the path of travel of the strip, one V-face of said female die member being opposed in spaced offset relation to a V-face of said male die member, a first pair of similar shear blades, said blades having securing apertures therein, the opposite ends of said pair of blades being of different length, a portion of said pair of blades being in shearing relation, said pair of blades being reversible to vary said portion, a second pair of blades on said main die members, said second blade abutting said first pair of blades, a pair of male lateral die members spaced from said main female die member, a pair of female lateral die members spaced from said main male die member, a third pair of similar shear blades, one of said third pair of shear blades being in shearing engagement with said first pair of shear blades, said third pair of blades forming a continuous shear edge with said first pair of blades the ends of said third pair of blades being beveled, the alternate male and female lateral dies carrying beveled blades interfitting with said beveled ends of said third pair of blades.

3. For use in a shear press having side guides and stop guides for producing a plurality of transformer core laminations from an elongated strip of transformer steel having a width corresponding to the width of the lamination

tion and a grain structure parallel to the longitudinal center line of the strip, said laminations having similarly shaped pointed opposite ends spaced inwardly from the edges of the strip with the apices of said points disposed on opposite sides of the longitudinal center line of the laminations, a waste eliminating shearing die, for simultaneously forming the ends of adjacent laminations, comprising a main V-shaped female die member, a main V-shaped male die member, said main die members being longitudinally arranged with respect to the path of travel of the strip, the apices of said main female and male die members being arranged in opposition and disposed on opposite sides of the center line of the path of travel of the strip, one V-face of said female die member being opposed in spaced offset relation to a V-face of said male die member, a first pair of similar shear blades, said blades having securing apertures therein, means engaging said apertures for securing said blades, one of said first pair of blades being secured to one of said opposed faces, the other of said first pair of blades being secured to the other of said opposed faces, a portion of said first pair of blades being in cooperating position, said blades being reversible to vary the length of said cooperating portion, a second pair of shear blades said second pair of shear blades being secured to the transverse V-faces of said main die members, said second blades abutting said first blades and forming a continuous cutting edge therewith, a pair of lateral male die members spaced from the V-faces of said female die member, a pair of lateral female die members spaced from said main male die member and from said lateral male die members, a third pair of similar shear blades, said third pair of blades being opposed to said first pair of blades, said third pair of blades forming a continuous cutting edge with said first pair of blades, said third pair of blades being reversible to maintain said continuity when said first pair of blades are reversed.

4. A waste eliminating shearing die for shearing similar pieces from a continuous strip comprising a main V-shaped female die member, a main V-shaped male die member, said main die members being longitudinally arranged with respect to the path of travel of the strip, the apices of said main female and male die members being arranged in opposition and disposed on opposite sides of the centerline of the path of travel of the strip, one V-face of said female die member being opposed in spaced offset relation to a V-face of said male die member, a first pair of similar shear blades, said blades having securing apertures therein, means engaging said apertures for securing said blades, one of said first pair of blades being secured to one of said opposed faces, the other of said first pair of blades being secured to the other of said opposed faces, a portion of said first pair of blades being in cooperating position, said blades being reversible to vary the length of said cooperating portion, a second pair of shear blades said second pair of shear blades being secured to the transverse V-faces of said main die members, said second blades abutting said first blades and forming a continuous cutting edge therewith, a pair of lateral male die members spaced from the V-faces of said female die member, a pair of lateral female die members spaced from said main male die member and from said lateral male die members, a third pair of similar shear blades, said third pair of blades being opposed to said first pair of blades, said third pair of blades forming a continuous cutting edge with said first pair of blades, said third pair of blades being reversible to maintain said continuity when said first pair of blades are reversed.
